UNITED STATES PATENT OFFICE

JOHN J. HENRY, OF MASON, ILLINOIS

FLYING MACHINE

Continuation of application Serial No. 446,628, filed April 23, 1930. This application filed June 3, 1931.
Serial No. 541,921.

This application is a continuation of my flying machine application Serial No. 446,628, filed April 23, 1930.

The present invention aims to provide a flying machine supplied with novel means for aiding the machine to rise, and the invention aims to provide a novel means whereby the blades are operated, controlled, and reversed, to have a lifting effect on the machine, when the blades move forwardly at the bottom of the frame of the machine, and when the blade moves backwardly at the top of the frame of the machine.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in side elevation, a flying machine constructed in accordance with the invention;

Figure 2 is a cross section on the line 2—2 of Figure 1;

Figure 3 is a top plan;

Figure 4 is a longitudinal section;

Figure 5 is an elevation of one track;

Figure 6 is a cross section showing one of the tracks and attendant parts;

Figure 7 is an elevation showing a portion of one of the tracks and parts associated therewith;

Figure 8 is a view illustrating a portion of the steering mechanism;

Figure 9 is an elevation disclosing the switch and parts adjacent to the switch.

The flying machine forming the subject matter of this application comprises a frame 1. At the forward end of the frame 1 and at the rear end thereof, there are lateral sustaining planes 2. A cab 3 is located at the rear end of the frame 1. At the forward end of the frame 1 there is an engine compartment 4. The frame 1 is carried on wheels 5, when in contact with the ground. The frame 1 includes upper rails 6, and lower rails 7, connected by curved portions 8. The upper rails 6, the lower rails 7, and the curved portions 8, are channel-shaped in cross section, as Figure 6 will show. The inner flanges 9 of the rails 6 and 7 and of the curved portions 8 are somewhat wider than the outer flanges 10. Loop-shaped tracks 11 are held in the frame parts 6, 7, and 8, and one of the tracks is shown in detail in Figures 5 and 9.

Each track 11 has a loop-shaped inner 65 groove 12 and an outer loop-shaped groove 14, separated by a rib 15, the grooves 12 and 14 merging into a single, substantially vertical straight groove 16 at the forward end of the track 11. The grooves 12 and 14 diverge, as shown at 50 and at 51, at the ends of said single groove 16. The groove 12 and 14 comprise substantially parallel horizontal parts 17 located at the top and at the bottom of the track 11. From the rear ends of said parallel parts 17, the grooves 12 and 14 diverge, to a place 52 (Figure 5) of maximum separation, located approximately midway between the top and the bottom of the track 11, at the rear end of the track.

Figure 9 shows that a pointed switch 53 is located at the place 50 where the grooves 12 and 14 diverge, and this switch is located at one end of the rib 15. The switch 53 is mounted to swing on a pivot element 54, carried by the track 11, and at its upper end, the switch has a heel 55 that extends into the groove 14. A spring 56 is engaged with the end of the rib 15, and with the switch 53, the spring being engaged around the pivot element 54.

The tendency of the spring 56 is to swing the switch 53 to the dotted position of Figure 9, the lower end of the switch being in engagement with the inner wall of the groove 12, the 5 switch extending across the groove 12, but during an operation to be described hereinafter, the switch 53 can be swung to the solid line position of Figure 9, the lower end of the switch engaging the outer wall of the 10 groove 14, the switch then extending across the groove 14.

The upper rails 6 and the lower rails 7 of the frame 1 are connected by bearing posts 19. The rails 6 and 7 are connected by struts 20, 15 disposed between the posts 19, longitudinally of the frame 1, as Figure 1 will show. The struts 20 are connected by cross bars 21 (Figure 4), and the cross bars and the struts carry supports 22, on which are mounted internal 20 combustion engines 23 driving shafts 24 journaled in the bearing posts 19, there being sprocket wheels 25 on the shafts 24, at each side of the frame 1.

The sprocket wheels 25 are engaged with 25 roller sprocket chains 26, which slide on the inner flanges 9 of the members 6, 7 and 8 of the frame 1, as indicated in Figure 6. Divers of links of the sprocket chains 26 have ears 27 (Figures 6 and 7) in which are journaled 30 short shafts 28, carrying blades 29, located between the chains 26.

The shafts 28 have forks 30, including 35 fingers 32, of the same length, one of these fingers being adapted to traverse the groove 14, the other of the fingers being adapted to traverse the groove 12, and both of the fingers being adapted to traverse the straight groove 16, as indicated at the left hand end of Figure 5. The width of the groove 16 is approximately 40 equal to the diameter of the fingers 32; the distance between the straight parallel parts 17 of the grooves 12 and 14 is less than the distance between the fingers 32; and the distance between the grooves 12 and 14, at 45 the place 52 of maximum separation (Figure 5) is approximately equal to the distance between the fingers 32.

When the engines 23 are put into operation, the shafts 24 are rotated, rotation being imparted to the sprocket wheels 25, and the sprocket chains 26 being driven. Starting with the blade which is in the position shown at 57 in Figure 5, this blade is horizontally disposed, at the rear end of the track 11, because the distance between the grooves 12 and 14, at the place 52 of maximum separation, is approximately equal to the distance between the fingers 32. The outer end 58 of the blade 57 is moving faster 55 than the inner end of the blade, and the back pressure of the air, in the direction of the arrow A, at the outer end of the blade, is greater than the back pressure of the air at the inner end of the blade. As a consequence, the outer end 58 of the blade 57 tends

to lag behind the inner end of the blade, as the blade moves downwardly from the position shown at 57 in Figure 5; and as the fingers 32 move into the straight parallel parts 17 of the grooves 12 and 14, at the bottom of the track 11, the blades, now in the position shown at the bottom of Figure 4, will be forwardly inclined from their lower edges to their upper edges, and as the blades advance, in the direction of the arrow B in Figure 4, 70, 75 the blades will have a lifting effect upon the machine.

The blades arrive at the vertical position shown at 59 in Figure 5, the blades being erected into that position because the width of the single groove 16 is approximately 80 equal to the diameter of the fingers 32.

The switch 53 is held in the dotted line position of Figure 9, with its lower end in engagement with the inner wall of the groove 12, by the action of the spring 56, the switch extending across groove 12. The uppermost finger 32 in Figure 9 therefore can not enter the groove 12, but must move along the switch 53, and enter the groove 14. The space between the fingers 32 is greater than the length of the switch 53, and before the lowermost finger 32 in Figure 9 can follow the uppermost finger, and enter the groove 14, the uppermost finger will have engaged 90 the heel 55 of the switch 53, and will have 95 swung the switch, against the action of the spring 56, to the solid line position of Figure 9, with the lower end of the switch in engagement with the outer wall of the groove 14. The switch 53 then extends across the groove 14, and directs the lowermost finger 32 of Figure 9 into the groove 12. As soon 100 as the lowermost finger 32 is clear of the switch 53, the switch swings back into the dotted line position of Figure 9, under the 105 impulse of the spring 56.

The blade 29 now moves backwardly, in the direction of the arrow C in Figure 4, the blades being backwardly inclined from their lower edges to their upper edges, and having 110 a lifting effect on the machine. The blades keep this position, and keep the oppositely inclined position shown at the bottom of the frame in Figure 4, since the distance between the parallel parts 17 of the grooves 12 and 14 is less than the distance 115 between the fingers 32.

As the blades 29 move downwardly in the direction of the arrow D in Figure 5, the blades assume the horizontal position shown 120 at 57 in that figure, because the grooves 12 and 14 diverge, from the rear ends of the parallel parts 17 of the grooves, to the place 52 of maximum separation.

An engine 35 in the compartment 4 drives a propeller 36. Through the instrumental 125 ity of any suitable mechanism 37, the engine 35 is connected to a throttle lever 38 located in the cab 3, conveniently to the operator's 130

seat 39. In advance of the operator's seat 39 is a steering wheel 40 connected to a shaft 41, journaled in the forward wall 42 of the cab 3. The shaft 41 has a depending arm 43, 5 provided at its lower end with a fork 44, receiving the forward end of a lever 45 which is fulcrumed at 46 on the cab 3. The rear end of the lever 45 is engaged with a fork 47 carried by an offset from a vertical shaft 48, 10 the shaft being journaled in bearings 49 on the cab 3. The shaft 48 carries a rudder 50.

It is clear that when the steering wheel 40 is rotated, the shaft 41 will operate the arm 43, and the arm will swing the lever 45, the 15 lever rocking the shaft 48, by means of the fork 47, and imparting the necessary movement to the rudder 50.

The device is simple in construction, but it affords a means whereby an upward component may be imparted to the movement of a flying machine, the sustaining qualities of the machine being promoted.

What is claimed is:—

1. A flying machine provided with tracks, 25 each track having loop-shaped inner and outer grooves which merge into a single substantially vertical groove at the forward end of the track, the loop-shaped grooves having upper and lower divergencies at the ends of 30 said single groove, and comprising substantially parallel and horizontal parts located at the top and at the bottom of the tracks, the loop-shaped grooves diverging, from the rear ends of said parallel parts, to a place of 35 maximum separation, located approximately midway between the top and the bottom of the track, at the rear end of the track, blades having fingers shaped to move in the respective loop-shaped grooves, and to move, together, in said single groove, means for holding 40 the blades spaced, and means for moving the blades in an orbit, the distance between the parallel parts of the grooves being less than the distance between the fingers, the 45 width of said single groove being approximately equal to the diameter of the fingers, and the distance between the grooves, at said place of maximum separation, being approximately equal to the distance between the fingers. 50

2. A flying machine constructed in accordance with claim 1, in combination with an automatically acting switch, yieldably actuated to a position in which it will shunt a forward finger of one blade into one loop-shaped groove at the upper of said divergencies, the switch being movable by said forward finger to a position in which the switch will shunt a rear finger of the same blade into 55 the other of said loop-shaped grooves.

3. A flying machine constructed in accordance with claim 1, in combination with a pivotally mounted, automatically acting switch, yieldably actuated to a position in 60 which it will shunt a forward finger of one

blade into one loop-shaped groove at the upper of said divergencies, the switch having a heel which projects into said one loop-shaped groove, said forward finger engaging the heel to move the switch to a position in which the switch will shunt a rear finger of the same 70 blade into the other of said loop-shaped grooves.

In testimony that I claim the foregoing as my own, I have hereto affixed my signature. 75
